FEEDING DEVICE FOR CABLE DRILLING TOOLS

Filed March 25, 1926

UNITED STATES PATENT OFFICE.

JOHN PENROD, OF OKMULGEE, OKLAHOMA, ASSIGNOR OF ONE-HALF TO ROBERT D. THOMPSON, OF OKMULGEE, OKLAHOMA.

FEEDING DEVICE FOR CABLE-DRILLING TOOLS.

Application filed March 25, 1926. Serial No. 97,294.

This invention relates to feeding devices for the wire lines of well drilling cable tools.

The present day feeding devices for the wire lines of cable drilling tools are in the nature of temper screws, the proper operation of which, to allow of the lowering of the drill cable, requires careful attention on the part of the driller and considerable time is required to return the temper screw to its set position at the end of its stroke. In addition to this an elaborate set of weights connected to the temper screw by cables is required to return the temper screw to its operative or set position and these features together with the danger incident to the employment of temper screws have been the subject of much consideration by those interested in the development of the industry and it is, therefore, an important object of this invention to provide a wire line feeding device by means of which the feed is rendered practically automatic and by means of which the return of the device to a set position is accomplished without the aid of separate weighted cables and without special effort on the part of the operator.

A further object of the invention is to provide a feeding device which may be positively locked in a set position to temporarily arrest further descent of the tools and which may be employed to lift the cable slightly should the device be employed in connection with a fishing operation.

A further and equally important object of this invention is to provide a feeding device of the character specified which may be employed in connection with standard drilling equipment without elaborate alteration of the same and without an increase in operating expenses.

Other objects and advantages will be apparent during the course of the following description.

In the accompanying drawing forming a part of this application and in which like numerals are employed to designate like parts throughout the same,

Figure 1 is a perspective of the improved cable or wire line feeding device;

Figure 2 is a sectional view through the same set for operation;

Figure 3 is a detail sectional view illustrating the device at the completion of a stroke or downward movement;

Figure 4 is a perspective of a sleeve or rotary valve embodied in the invention;

Figure 5 is a detail sectional view through a modified form of invention.

In the drawing, wherein for the purpose of illustration is shown several preferred embodiments of the invention, the numerals 5 and 6 designate inner and outer cylinders, respectively, which, as shown in Figure 2, are arranged in spaced relation to define an annular compression chamber 7 adapted for the reception of air under pressure. The chamber 7 may be supplied with air by way of a valve 4. The valve 4 may when the occasion requires be connected with an air compressor or with a hand pump so that pressure to the desired amount will be present in the chamber 7.

The upper portion of the cylinders 5 and 6 have threaded connection with a head 8. More specifically, the head 8 is internally screw threaded at two points for the reception of the external threads on the upper portions of the cylinders 5 and 6. The head 8 is provided with a neck 9 having laterally projecting arms 10 adapted to be engaged with a beam in the usual and well known manner so that the operation of the beam will result in the vertical movement of the feeding device just as are the present day temper screws raised and lowered.

Figure 2 plainly illustrates that a quantity of heavy oil is received in the cylinders 5 and 6 and is normally urged into the inner cylinder 5 by the pressure of the air within the chamber 7. At this point it might be stated that the air is introduced into the chamber 7 under pressure when the major portion of the liquid is contained within the inner cylinder 5 as shown in Figure 2. Therefore, when the liquid is forced from the inner cylinder 5 into the chamber 7 by a means to be described the air within the chamber 7 is still further compressed.

A suitably packed piston 16 is mounted in the cylinder 5 and has connection with a plunger or rod 17 which extends down through the lower end of the device and is connected with what might be said to be a crosshead 20. The crosshead is threaded onto the lower end of the rod 17 and is further held thereon by means of a nut 22 or other secure fastening device. Suitable links 24 are connected to the crosshead 20

and carry a clamp 26 of conventional or other design.

The column of liquid in the inner cylinder 5 supports the piston 16 and when the 5 column of liquid is free to flow from the inner cylinder 5 to the chamber 7 through a port 28 the piston 16 may descend to allow of the lowering of the wire line and drilling tools. As shown in Figure 2, a 10 sleeve valve 30 is mounted in the lower portion of the cylinder 5 and the bottom member 32 and is provided with ports 34 and 36 adapted to be selectively registered with the port 28. When the port 34 is in registration with the port 28 the piston may 15 descend at a comparatively slow uniform rate.

The sleeve valve 30 may be turned so that the port 36 which is in the nature of an arcuate slot may be registered with the port 20 28 to bring about the somewhat more rapid descent of the piston. It will be seen that when the piston 16 reaches the limit of its 25 descent the air in the chamber 7 will be very highly compressed and when the weight of the tools is taken off the clamp this highly compressed air will act to promptly return the piston 16 to an elevated position. Of course, when the piston reaches the limit of its descent and it is desired to return the 30 same to an elevated position as shown in Figure 2 the valve 30 is moved to its completely closed position and the clamp 26 released from binding engagement with the wire line. The valve 30 is now turned so 35 that the port 36 registers with the opening 28 and the air under pressure in the chamber 7 will return the liquid to the cylinder 5 whereupon the piston 16 is returned to an elevated position. All of this is accomplished without the aid of an elaborate arrangement of weights or pulleys so necessary in the present day temper screws. Also this 40 re-setting operation is completed without the loss of the driller's time.

Figure 4 illustrates that the sleeve 30 is provided with a radial handle 40 which extends through a suitable slot in the lower end member 32 and is within convenient reach of the operator so that it is a simple 45 matter to turn the valve to the desired position.

One of the most important features of the invention resides in the fact that the piston 16 and all parts of the device are positively 50 held against turning under the influence of the back twist in the line by the provision of a squared shaft 50 which extends up from the piston 16 and passes through a squared opening in the head 8, and the neck 9. Since 55 the arms 10 are mounted on the beam and are held against turning thereby the cylinder 6 and all other parts of the device are positively held against turning.

Should it be desired to lift the tools off 60 the bottom slightly or to raise the wire line

during a fishing operation, a hand pump consisting of a plunger 60 and a hand operated lever 61 may be brought into use and a quantity of the liquid in the chamber 7 pumped from the chamber 7 into the cylinder 5. The lever 61 which is fulcrumed as indicated at 63 may be rocked to reciprocate the plunger 60 and thereby allow a portion of the liquid in the chamber 7 to pass down through a port into the small cylinder in 70 which the plunger 60 reciprocates and on the forward motion of the plunger 60 the oil or other liquid employed will be forced up into the cylinder 5. This, of course, will 75 result in the upward movement of the piston 80 16 the required distance.

In the use of the improved feeding device the laterally projecting arms 10 are mounted on the beam in the usual manner and the wire line engaged by the clamps 26. The beam is now set in motion in the usual manner and to bring about the feeding of the cable at the proper rate, the valve handle 40 is moved to one of its extreme positions to register the port 34 with the port 28 whereupon the liquid beneath the piston 16 will bleed through the port 28 and into the chamber 7. If it is desired to drop the wire line possibly a foot, the sleeve valve 30 may be moved to its other extreme position so 95 that the port 36 will register with the port 28 and the more rapid flow of the liquid from the cylinder 5 to the chamber 7 brought about.

When the piston 16 reaches the limit of its 100 descent the valve 30 may be moved to its fully closed position and the clamps released. The valve 30 is now moved to a position where the port 36 registers with the port 28 and the highly compressed air in the chamber 7 will promptly cause the oil or other liquid to return to the cylinder 5 and elevate the piston 16 so that the improved feeding device is again ready for 105 operation.

In the form of invention shown in Figure 5 the lower end member which is designated by the numeral 70 is provided with a valve housing 71 in which a needle valve 72 is located. The needle valve 72 controls a 110 passage 74 extending from the inner cylinder to the outer air chamber and by the operation of the handle of the valve the flow of fluid back and forth through the port 74 may be accurately regulated.

The invention forming the subject matter of this application is intended to provide a combined hydraulic and compressed air means by which the uniform advancement or feed of the wire line is accomplished without frequent adjustment by the driller.

As previously stated, the improved feeding device or any of the parts thereof are positively held against turning under the influence of the back lash in the line and 125 130

the device is thereby rendered extremely safe.

Having thus described the invention, what is claimed is:

- 5 1. A hydraulic feeding device for wire lines comprising inner and outer communicating cylinders adapted for the reception of compressible and non-compressible fluids, a piston in one of the cylinders and having a rod adapted for connection with a wire line, a sleeve valve having ports adapted to establish communication between the inner and outer cylinders, and means whereby one of the cylinders may be supplied with 15 a fluid under a high pressure.
2. A feeding device for the character specified comprising inner and outer interfitting cylinders, end members closing and connecting the cylinders, said cylinders being adapted for the reception of compressible and non-compressible fluids, a piston in the inner cylinder and having a rod adapted for connection with the wire line of cable tools, means whereby fluid may be 25 introduced into and compressed in said outer cylinder independently of the non-compressible fluid and the piston, a valve control-

ling communication between the inner and outer cylinders and adapted to allow of the movement of a non-compressible fluid from the inner cylinder to the outer cylinder, whereby the piston may descend under the weight of the wire line and the cable and the tools connected thereto, the movement of the non-compressible fluid from the inner to the outer cylinder constituting a means to further compress the compressible fluid in the outer cylinder whereby the highly compressed fluid in the outer cylinder may return the non-compressible fluid to the inner cylinder to elevate the position therein. 30 35

3. A feeding device for wire lines of cable drilling tools comprising inner and outer interfitting cylinders adapted for the reception of fluid, a piston in one of the cylinders and having a rod adapted for connection with a wire line, a sleeve valve within one of said cylinders and having separate ports of different sizes adapted to permit of the flow of fluid from one cylinder to the other whereby the piston may be raised or lowered. 40 45 50

In testimony whereof I affix my signature.
JOHN PENROD.
